UNITED STATES PATENT OFFICE.

ROBERT BRUCE MUSSER, OF SEATTLE, WASHINGTON.

REFRIGERATING DEVICE.

Application filed June 30, 1921. Serial No. 481,456.

To all whom it may concern:

Be it known that I, ROBERT BRUCE MUSSER, a citizen of the United States, residing at Seattle, in the county of King and State of Washington, have invented certain new and useful Refrigerating Devices, of which the following is a specification.

My invention relates to the art of refrigerating devices. More particularly, my invention relates to a refrigerating device which utilizes a refrigerating fluid as a brine to cool the air of the refrigerator room or compartment.

While my invention will be described particularly as applied to refrigeration in a meat packing plant, it is to be understood that the same is not to be limited to any such specific use.

As heretofore designed, the refrigerating means has failed to produce an active, positive circulation of air, and failed to provide for the efficient removal of moisture arising from steaming meat freshly supplied to the room, or moisture otherwise present, with the result that the ceiling and walls of such refrigerating rooms are constantly coated with large drops of moisture which may or may not freeze, depending upon the purpose of the particular room—it being understood that some of the refrigerating rooms are maintained below the freezing point while others are not. Such water thus falls upon the meat. If said drops of water freeze upon said walls, then we have a constantly increasing coating of ice, which must be removed from time to time. The pipes in either case become coated with ice due to the moisture deposited upon them.

The failure to provide for removing the moisture from the air of the refrigerating room constitutes a constant danger to health, because the employees, when acclimated to summer temperature, must, during the hours of employment, enter and remain in the cold, damp air of such rooms for periods of considerable duration. This applies to a large per cent of the employees of a meat packing plant. The cold, damp air of such rooms renders it impossible for any except the most hardy employees to perform the necessary work of hanging up, sorting, taking stock, changing the pickle, and arranging of the meats in such rooms during the chilling, curing and freezing processes.

Such great moisture in the air of such rooms defeats, to a great extent, the very

purpose of such refrigerating rooms in that meats do not keep well in moisture-laden air, and many articles of produce absolutely require a dry air. The meat becomes slimy in such moisture-laden air, and so pronounced is this that in the case of some meats the slime appears in twenty-four hours.

Furthermore, the more efficient modern means of refrigerating require many hundreds of feet of piping about the refrigerating room or compartment, and hence are very expensive. Such piping involves much waste of space and is otherwise inconvenient. Besides this piping means of employing the refrigerating fluid, another means is to use the "open brine" system. This involves constructing the refrigerating room two stories high, and the fluid is caused to fall as a shower in the upper half of such double room. The fluid falls upon a collecting floor which forms the ceiling of the lower half of said room—said floor extending only part way across the room so that openings are provided at both sides of the said "ceiling" to permit the cooled air to descend on one side of the room and warm air to rise on the other. Such means obviously is objectionable in wasting space (extra "loft" being requisite) and the very cold floor of this "loft" being the ceiling of the lower half, which is the only part available for refrigerating, is always very heavily coated with water, since said "floor ceiling" is located to best advantage to condense the moisture in the air of the refrigerating part of the room. Heavily insulating said "floor-ceiling" has been of no avail in overcoming this condensation of the moisture.

In general, the objects of my invention are to overcome the above objections to such refrigerating means. More particularly, the objects of my invention are: To provide a refrigerating device greatly more efficient and sanitary than the means heretofore used; to provide for a refrigerating device which causes a positive and forced circulation of air; to provide such a device which will effectively remove all objectionable moisture from the air of the refrigerating room; to provide such a device that will, also, purify the air of such room by removing the impurities therefrom; and to provide such a device which is adapted to be used for inducing refrigeration in one or more rooms.

The above mentioned general objects of my invention, together with others inherent

in the same, are attained by the device illustrated in the following drawings, the same being merely a preferred exemplary form of embodiment of my invention, throughout which drawings like reference numerals indicate like parts:

Figure 1 is a side view of a device embodying my invention, said device being shown partly in section and part broken away;

Fig. 2 is a view in section on broken line 2, 2 of Figure 1;

Fig. 3 is a view of the open trough cover;

Fig. 4 is a view in transverse section of the cylinder on broken lines 4, 4 of Fig. 2; and

Fig. 5 is a sectional view of a refrigerating room partition provided with my invention having a deflector so that the cold air may be deflected into either room.

A cylinder 6, preferably of thin sheet metal, is disposed vertically with open ends 7 and 8. One or more of these cylinders, as the size of the room may require, are disposed along one side only of the refrigerating room, preferably between the studding 9 so that no loss of space is incurred. For a room 30 ft. long by 12 ft. wide and 9 ft. high, in general, I find three such cylinders 30 to be more than ample for maintaining a temperature of 38°. A pipe 10 connected to a source of refrigerating fluid, such as brine, extends along the top of the cylinders 6 near the ceiling, and the fluid in said pipe 35 10 is jetted into the upper end portion of said cylinders through nozzles 11. The fluid is sprayed out in a thin sheet form so that a jet is formed that drives the air in said cylinder downwardly, said fluid, being held 40 by the force of adhesion, clings to the walls of said cylinder for the most part throughout its descent.

At the bottom of the said cylinder is the trough 12, preferably having the removable cover 13, said cover being provided with the slot 14. Such cover guards against splashing of the brine, and permits the free discharge of the cold air through the slot 14. A board wall 15 having perforations 50 16 and removable panels 17, may be provided to extend halfway up the room as a guard to the said cylinders.

The deflector 18 is preferably provided to deflect the cold air downwardly towards the floor, so that it is obliged to travel the greatest distance possible in reaching the ceiling, and hence perform most fully its function of cooling the air.

In Fig. 5 a partition of a refrigerating room is shown in cross section with a device embodying my invention wherein is provided an adjustable deflector 19 so that the cold air may be deflected into the room on either side of said partition, or into both rooms simultaneously—the wall 15 herein

being shown as extending nearly to the ceiling. The providing of this wall 15, as well as the extent—it is to extend to the ceiling—is optional.

A valve 20 controls the flow of the refrigerating fluid to the pipe 10, and pipe 21 serves to draw off the fluid from the trough 12.

The mode of operation of my invention is as follows:

The refrigerating fluid, such as brine, is rendered cold by any of the methods well-known to those acquainted with the art, and is conducted in the pipe 10 to the room or compartment to be refrigerated. In such room said pipe being disposed near the ceiling, the refrigerating fluid is jetted forcibly from the nozzle 11 against the wall of the cylinder. The sheet of fluid formed by the brine constitutes, as it were, a jet, which drives the air downwardly out of the cylinder and ejects said air from the lower end of the cylinder; that is, close to the floor so that as said cold air absorbs heat, it gradually rises, being forcibly displaced upwardly by the ensuing still colder air—it, of course, being well-known that the cold air occupies the lowermost parts of the room while the warmer air takes its position near the ceiling.

The refrigerating fluid must be jetted against the side walls, so that said fluid forms as nearly a complete envelope across the cylinder as possible, in order that the warmer air drawn in may be caused to pass down practically the full length of cylinder 6. By experiment it has been found that the cone of fluid formed by the spray should leave the nozzle at approximately the angle of forty-five (45°) degrees to the horizontal. This has been found to produce most efficient operation of the refrigerating fluid in extracting the heat from the air entrapped.

The said air is not only thus forced down the cylinder by means of the jetting or "piston-like" action of the fluid, but said air is exposed to the refrigerating effect of the said fluid spread out in a continuous sheet over the wall of the cylinder, and hence its precipitation downwardly is augmented by being rendered very cold. In this wise, my invention provides for the co-operation of two forces to induce the downwardly directed current of air in the cylinders, namely, the force of the jetting or "piston-like" action of the fluid, and the cooling of the air. In this manner, a very strong current downwardly is provided, which keeps all the air of the room or compartment in a state of continuous motion or circulation. It is clear that the force of the circulation may be regulated by changing the pressure of the fluid being jetted. In this manner and by the number of cylinders installed, the de-

gree of refrigerating can be regulated to a nicety as required by the various meats.

The drawing of the warmer air of the room (however cold such air may be relatively) into the open upper end 7 and exposing of such air to the very cold refrigerating fluid on the walls of the cylinder causes the objectionable moisture in said air to be precipitated in the fluid solution, and hence dilutes said fluid to such an extent that periodically such surplus water must be evaporated, or, in the case of brine, more salt added to maintain the strength or density of said brine. It is to be understood that the continuous introduction of freshly slaughtered meat or cooked meats adds a great deal of moisture to the air of the room, and the same is clearly visible as it rises in the form of steam, and obliquely 20 directly to the upper end of said cylinders 6. Also, such moisture interferes seriously with the evenness of the temperature of the room. The entrapping and passing of the air by the jetted fluid and the setting of said 25 air into a whirling motion as it comes into contact with the falling fluid "walls" on the inside of the cylinder during the descent therethrough washes it thoroughly and removes its impurities much as the air is 30 washed in ventilating systems.

This washing of and the aforementioned removal of the objectionable moisture from the air produces a most sanitary and a very cold, dry air for refrigeration.

The reason for the great efficiency of such refrigerating mechanism is now manifest. The rapid circulation of the air and the constant removal of the objectionable moisture gives a more uniform temperature throughout the room. A given quantity of fluid is utilized to the greatest advantage, in that it is first made to induce a strong, positive circulation of the air of the room or compartment, and in so doing, said refrigerating fluid is disposed in such a form as to make its cooling properties most effective—that is, it is caused to line in a thin sheet the cylinder 6, or the fluid may be considered as forming a cylinder in cylinder 6, whose walls are formed of fluid, and are continuously falling, so that new contact with and violent agitation of the air in the cylinder 6 is produced. The quantity of refrigerating fluid represented by thirty lineal feet of pipe utilized in connection with my invention has been found to perform a refrigerating service greatly in excess of that supplied by that quantity of such fluid confined in a thousand feet of pipe when utilized as commonly heretofore designed.

All such efficiency and the elimination of the great quantities of piping clearly and for manifest reasons provide for a most economical refrigerating device. Instead of

maintaining a very low temperature in a great quantity of piping, and absorbing the heat from the comparatively still, inert mass of air bounded by the room or compartment, my invention provides for using a small quantity of fluid piping, inducing a rapid circulation of the air in the refrigerating room, removing the moisture therefrom and washing said air.

The cylinder 6 of my invention may be disposed between the post or studding of a partition without the loss of any working space, and the cold air deflected alternately or simultaneously into the refrigerator room on either side by the adjustable deflector 19. The efficiency of my invention renders it peculiarly applicable to window refrigerating compartments now commonly located in the fronts of restaurants and meat markets.

Obviously, changes may be made in the forms, dimensions, and arrangement of the parts of my invention, without departing from the principle thereof, the above setting forth only a preferred form of embodiment.

I claim:

1. A refrigerating device embodying a compartment; one or more vertically disposed cylinders therein, extending from near the ceiling of said compartment to near the floor thereof; a nozzle axially disposed in the upper end portion of said cylinder; a trough disposed beneath the lower end portion of said cylinder; a pipe connecting said nozzle with a source of refrigerating fluid; a second pipe connecting said trough with said source of refrigerating fluid; and means whereby said fluid may be jetted from said nozzle against the walls of said cylinder, whereby the air from the upper portion of said compartment may be forced downwardly, by means of said jet action and by reason of the weight of the cooled air through said cylinder and ejected from the lower end portion of said cylinder.

2. In combination with a refrigerating device embodying a compartment; a vertically disposed cylinder open at both ends, said cylinder extending nearly to the top and bottom of said compartment; a nozzle axially disposed in the upper end portion of said cylinder; and a collecting means at the bottom of said cylinder, whereby a refrigerating fluid may be jetted from said nozzle against the inner walls of said cylinder and collected in said collecting means.

3. A refrigerating device embodying a compartment divided into two sections by a partition; one or more vertically disposed cylinders in the partition between said compartments, said cylinders extending from near the ceiling of said compartment to near the floor thereof; a nozzle axially disposed in the upper end portion of said cylinder; a trough disposed beneath the lower end por-

tion of said cylinder; a pipe connecting said nozzle with a source of refrigerating fluid; a second pipe connecting said trough with said source of refrigerating fluid; means whereby said fluid may be jetted from said nozzle against the walls of said cylinder, whereby the air from the upper portion of either of said compartments may be forced downwardly, by means of said jet action

and by reason of the weight of the cooled air through said cylinder and ejected from the lower end portion of said cylinder; and an adjustable deflector, whereby the said air may be discharged into one or both of said sections. 15

In witness whereof, I hereunto subscribe my name this 21st day of June 1921.

ROBERT BRUCE MUSSER.
